UNITED STATES PATENT OFFICE.

GEORGE L. BARNEY AND JOHN S. KITTLE, OF INDIANAPOLIS, INDIANA.

DESIGN FOR A LOCK-BOX FRONT.

SPECIFICATION forming part of Design No. 28,315, dated February 22, 1898.

Application filed September 9, 1897. Serial No. 651,388. Term of patent 7 years.

To all whom it may concern:

Be it known that we, GEORGE L. BARNEY and JOHN S. KITTLE, citizens of the United States, residing at Indianapolis, in the county 5 of Marion and State of Indiana, have invented and produced a new and original Design for Post-Office Lock-Box Fronts, of which the following is a specification.

As shown in the drawing, the leading or 10 material features of our design consist of an eagle in relief with wings extended preparatory to flight, with head to the side and holding in its claws an olive branch and bunch of 15 arrows, all upon a stippled, matted, or roughened background, transversed or partially

covered by groups of ribs or rays in relief, the box-front to be rectangular in outline, with two disks in the upper face of the plate, as shown, and with a rectangular panel in the lower face of plate, as shown.

Having described our invention, what we claim as new, and desire to secure by Letters Patent, is—

The design for a post-office lock-box front, as herein shown and described.

GEORGE L. BARNEY.
JOHN S. KITTLE.
